UNITED STATES PATENT OFFICE.

OMAR J. HOTALING, OF JOHNSTOWN, NEW YORK.

COIN-CONTROLLED APPARATUS FOR VENDING-MACHINES.

992,774.

Specification of Letters Patent.

Patented May 23, 1911.

Application filed August 2, 1910. Serial No. 575,061.

To all whom it may concern:

Be it known that I, OMAR J. HOTALING, a citizen of the United States, and a resident of Johnstown, in the county of Fulton and 5 State of New York, have invented a new and Improved Coin-Controlled Apparatus for Vending-Machines, of which the following is a full, clear, and exact description.

This invention relates to coin-controlled 10 apparatus for use in connection with different kinds of vending machines, and has reference more particularly to apparatus of this class associated with an operating lever or member of the vending machine, and comprising 15 a displaceable stop for limiting the travel of the member, normally inoperative means for displacing the stop through the movement of the member itself, and means for rendering the first-mentioned means operative 20 by the member when a coin is introduced into the apparatus.

The object of the invention is to provide a simple and efficient coin-controlled apparatus which can be used with different kinds 25 of vending machines, which serves to prevent the operation of the machine with which it is employed unless the suitable predetermined coins are introduced into the coin slot, which can be adjusted to operate 30 with one or more coins of different kinds, which requires comparatively little power to actuate it, which does not modify or otherwise affect the operation of the vending machine itself, and which is so constructed 35 that unauthorized or improper operation thereof is accomplished only with difficulty.

The invention consists in the construction 40 and combination of parts to be more fully described hereinafter and fully set forth in the claims.

Reference is to be had to the accompanying 45 drawings forming a part of this specification, in which similar characters of reference indicate corresponding parts in all the views, and in which—

Figure 1 is a side elevation of an embodiment of my invention; Fig. 2 is a front elevation of the apparatus showing parts in cross section; Fig. 3 is a transverse section 50 of part of the device showing the coin passage; Fig. 4 is an enlarged view similar to Fig. 2, showing certain of the parts in different positions; Fig. 5 is a side elevation of a detail of modified form; and Fig. 6 is 55 a view similar to Fig. 5, showing a detail of further modified form.

Before proceeding to a more detailed explanation of my invention, it should be clearly understood that while the coin-controlled apparatus is particularly useful with the type of vending machine shown in my United States Patent application, Serial No. 537,452, filed January 11, 1910, it can also be advantageously employed with other vending machines employing an operating lever or member by means of which the coin-controlled mechanism itself can be operated. As will appear more clearly hereinafter, it can be adjusted for use with one or more coins, and it is thus adapted for the vending of articles having different values. For example it can be employed with a machine for selling daily papers at one cent apiece, or with papers costing two or three cents. The scope of the machine is thus increased, and the necessary alteration is slight, so that little inconvenience results therefrom. Certain of the details form no part of my invention, and can be varied in accordance with individual preference and special conditions, without departing from the underlying spirit of the invention.

Referring more particularly to the drawings, I have shown the operating lever or pivoted member 10 of a vending machine, mounted to swing about a suitable pivot 11, at one end thereof. The lever 10 extends removably through a slotted guideway 12 formed between spaced parallel bars 13 and 14. The bar 13 has extensions 15 to which the bar 14 is secured by means of screws 16 or in any other suitable manner. The bar 13 can be fastened to a wall or other part of the vending machine, by means of screws 17 or the like.

The bar 14 has mounted thereon a coin casing 18 in which is formed a slot 19, constituting the coin passage through which the coins travel. A suitable coin chute or like device (not shown), is used in connection with the vending machine for directing the coins to the coin passage. The slot 19, forming the coin passage, is open at the front of the casing 18, and has pivoted therein the coin keeper 20, consisting of an elongated, 105 comparatively thin strip of metal, pivotally mounted at its upper end by means of a suitable pin 21. A light spring 22 is fastened to the lower portion of the coin casing, and at the corresponding extremity of 110 the keeper. It tends to displace the keeper from its normal position within the slot, and

substantially parallel to the length thereof. The keeper, at its inner end has a projection 23 for a purpose which will appear hereinafter. A releasing member 24 consisting of 5 a bell crank lever having a long arm 25 and a short arm 26, is pivotally mounted by means of a screw 27 or the like, upon the bar above the coin casing. The arm 26 at the lower end has a laterally disposed finger 10 28 which extends transversely of the keeper 20, and in a normal position of the releasing member engages the keeper and tends to hold it in operative position within the coin 15 passage slot. The arm 25 at its free end has a laterally disposed finger 29 which is engaged by a strip spring 30 secured upon the operating lever 10. The spring 30 when the lever is in its normal elevated position, holds the releasing member in a normal position 20 such that the keeper 20 is operative.

A movable stop 31 is mounted upon the coin casing by means of an offset strap guide 32, held in place by means of screws 33, or in any other suitable manner. The stop 31 25 has the end provided with a bevel 34 at the under side, and at the rear end has an extension 35 pivotally connected by means of a pin 36 with a lever 37. The latter is movably mounted by means of a pin 38 upon a 30 bracket 39, carried by the bar 14. The lever 37 forms one element of a lever system which comprises in addition, a lever 40 movably mounted by means of a pivot pin 41 upon a bracket 42 carried upon the back plate 43 35 of the coin casing. The levers 37 and 40 are connected at their lower ends by means of a link 44 which is pivoted at the extremities of the levers by means of suitable pivot pins or rivets 45. A strip spring 46 is 40 mounted upon an extension 47 of the bar 14 and engages at the lower end of the lever 40, to hold the lever system in a normal position such that the stop 31 is projected into the path of the operating member 10 in the 45 guide way 12, as is shown most clearly in Fig. 2.

The coin casing has cylindrical openings 48 and 49 formed therein, which extend transversely of the coin passage 19, and are 50 located respectively at opposite sides thereof, the opening 48 registering with the opening 50 in the bar 14. The opening 48 at the end adjacent to the opening 50 has an enlarged part 51 which is equal in 55 diameter to the opening 50. At the other end the opening 48 has an inwardly disposed flange 52 forming a constricted neck, and has at the outside of the flange an enlarged part 53. The opening 49 at the end 60 adjacent to the coin passage 19 has an enlarged part 54. The back plate 43 of the coin casing has a circular recess 55 which is adjacent to the opening 49 and communicates therewith through a reduced opening 65 56. I employ a plunger device for actuating

the stop 31 through the lever system. The plunger device consists of an inner member 57 located in the opening 48, and an outer member 58 located in the opening 49. The member 57 has an enlarged head 59 which 70 guidingly engages within the opening 48 and which is provided with a laterally extended crown 60 having the outer surface 61 beveled, which is located movably in the opening 50 of the bar 14, and is adapted to 75 seat in the enlarged part 51 of the opening 48 when the member 57 is retracted, as is shown in Fig. 4. At the other end, the member 57 has a laterally extended disk 62 adapted to seat in the enlarged part 53 of 80 the opening 48 when the member 57 is projected. A spring 63 is mounted upon the member 57 and engages the flange 52 and the head 59. It tends normally to hold the member 57 projected so that the beveled end 85 face 61 of the crown 60 projects into the path of the operating member 10. The member 58 at the rear end has an enlarged head 64 which normally seats in the recess 55 and is engaged by the upper end of the lever 40. 90 At the other end, the member 58 has a laterally extended disk 65 which is movable in the enlarged part 54 of the opening 49. A helical spring 66 is mounted about the member 58 and engages the disk 65 and the 95 back plate 43. It tends to hold the member 58 in position such that the head 54 seats in the recess 55.

The operating member 10 in its normal position is elevated as shown in Fig. 1. 100 The member 57, under the influence of the spring 63, is positioned with the crown 60 projecting into the guideway 12. The member 58 under the influence of the spring 66 is positioned with the head 64 seated in the 105 recess 55, and the disk 65 with its end face substantially flush with the wall of the coin passage 19. The end face of the disk 62 is substantially flush with the opposite wall of the coin passage. The spring 46, when the 110 head 64 is retracted, holds the lever system so that the stop 31 projects into the guideway 12. When a coin is introduced into the coin passage so that the vending machine can be operated, it is brought to a 115 stop between the disks 62 and 65 by the stop projection 23 of the member 20, which is located at a suitable point of the keeper for this purpose. After the coin is in place, the operating member 10 is depressed and moved 120 along the coin passage. It comes into engagement with the beveled end face of the crown 60 and thereby displaces the member 57 against the tension of the spring 63. The interposition of the coin 67 between the disks 125 62 and 65 permits the movement of the member 57 to be transmitted to the member 58 so that the head 64 is forced outward and actuates the lever 40. The movement of the lever 40 is transmitted through the link 44 and the lever 130

37, to the stop 31, which is retracted from the path of the operating member, and permits this to be moved to the end of its travel in the guideway 12. It will be understood 5 that unless the stop 31 is retracted, the operating member 10 cannot pass beyond the stop, and in consequence, the vending machine cannot be operated. The lever system is so constructed that the movement of the 10 member 58 is multiplied materially in being transmitted to the stop, so that a comparatively slight movement on the part of the head 64 is sufficient to move the stop completely out of the path of the operating 15 member. When a coin is not positioned between the disks 62 and 65, a movement of the member 59 cannot be transmitted to the member 58.

After the operating member passes beyond the stop 31, the spring 30 no longer engages the arm 25 of the releasing member, and this gravitationally swings from engagement with the keeper. The spring 22 then displaces the keeper, as is shown in Fig. 25 3, and the coin can fall from between the disks of the plunger device, and escape at the lower end of the coin passage into a suitable coin receptacle, not shown. In Figs. 5 and 6, however, are shown modified forms 30 of the keeper 20. In the first of these the keeper 68 is similar in all respects to the keeper 20, with the exception of the projection 69, which is located lower upon the keeper than is the projection 23. This necessitates the introduction of more than one 35 coin; for example, two coins can be positioned between the plunger disks. In other words, if it is desired to vend newspapers costing two cents apiece, it is necessary to insert two separate cents, the first of which is supported by the projection 69, and the second of which is held in position between the plunger disks, by the first one. In Fig. 40 6 I have shown a keeper 70 having the projection 71 so positioned that three coins must be introduced before the device will operate.

Having thus described my invention, I claim as new, and desire to secure by Letters Patent:

50 1. Apparatus of the class described, comprising an operating member, a stop normally operative to limit the movement of said member, a plunger device adapted to receive a coin and having a part adapted to 55 be actuated by said member, and a second part adapted to be actuated by said first part when a coin is interposed between said parts, means for directing a coin into position between said parts, and an operative connection between said second part and said stop.

2. Apparatus of the class described, comprising an operating member, a displaceable stop for limiting the travel of said member, elements for operatively connect-

ing said member and said stop to permit said stop to be displaced by a movement of said member, and means for introducing a coin between said elements, said elements to render the same relatively operative being 70 normally inoperative with respect to one another.

3. Apparatus of the class described, comprising an operating member, a displaceable stop for limiting the travel of said member, 75 elements for operatively connecting said member and said stop to permit said stop to be displaced by an initial movement of said member, means for introducing a coin between said elements, said elements being normally inoperative with respect to one another, and means operable by a further movement of said member for displacing a coin from between said elements.

4. Apparatus of the class described, comprising an operating member, a displaceable stop for limiting the travel of said member, elements for operatively connecting said member and said stop, to permit said stop to be displaced by an initial movement of said member, a coin passage for introducing a coin between said elements, said elements being normally inoperative with respect to one another, a keeper for holding said coin in position between said elements, and means 90 controlled by said operating member for maintaining said keeper in an operative position during a part of the travel of said member.

5. Apparatus of the class described, comprising an operating member, a displaceable stop for limiting the travel of said member and normally projecting into the path of said member, a coin passage, plunger parts arranged at opposite sides of said passage, 105 one of said parts normally projecting into the path of said member, and a lever system for operatively connecting the other of said parts and said stop.

6. Apparatus of the class described, comprising an operating member, a displaceable stop for limiting the travel of said member and normally projecting into the path of said member, a coin passage, plunger parts arranged at opposite sides of said 110 passage, one of said parts normally projecting into the path of said member, a lever system for operatively connecting the other of said parts and said stop, a keeper movably mounted adjacent to said passage, and 115 serving to hold a coin in position between said parts, and a member controlled by said operating member and serving to position said member operatively until said operating member passes said first part of said 120 plunger.

7. Apparatus of the class described, comprising an operating member, a stop normally projecting into the path of said member to limit the travel thereof, a casing hav- 130

ing a coin passage, plunger parts movably arranged in said casing at opposite sides of said passage and adapted to be operatively connected by the interposition of a coin 5 therebetween, springs tending to hold said parts in normal positions such that one of said parts projects into the path of said member, and a lever system operatively connecting the other of said plunger parts and 10 said stop, whereby said operating member can actuate said stop to displace the same from its path.

8. Apparatus of the class described, comprising an operating member, a stop normally projecting into the path of said member to limit the travel thereof, a casing having a coin passage, plunger parts movably arranged in said casing at opposite sides of said passage and adapted to be operatively 15 connected by the interposition of a coin therebetween, springs tending to hold said parts in normal positions such that one of said parts projects into the path of said member, a lever system operatively connecting the other of said plunger parts and said stop, whereby said operating member can actuate said stop to displace the same from its path, a keeper movably carried by said casing at said passage and adapted to hold 20 a coin in position between said parts, and a releasing member normally engaging said keeper to hold the same in operative position and controlled by said operating member.

35 9. Apparatus of the class described, comprising an operating member, a displaceable stop, a coin-receiving device operatively connected with said stop and adapted to be actuated by said member, said coin-receiving 40 device being normally inoperative, and being rendered operative by the introduction of a coin, a movable member normally operative to hold a coin in position at said coin-receiving device, a spring tending to release 45 said keeper, a releasing member normally

holding said keeper in an operative position, and a spring carried by said operating member and engaging said releasing member to hold the same operative during the initial part of the travel of said operating 50 member.

10. Apparatus of the class described, comprising an operating member, a guideway for said operating member, a coin-casing mounted adjacent to said guideway and having a coin passage therethrough, said coin casing having registering openings therethrough at opposite sides of said passage, plunger parts mounted in said openings, springs tending to hold said parts in normal 55 positions, such that the adjacent ends of said parts are separated at said coin passage to receive a coin therebetween, the first of said parts normally projecting into the path of said operating member, a lever system operatively connecting the second of said parts and said stop, and serving to multiply the movement of said second part in transmitting the movement to said stop, a spring for holding said lever system in a normal 60 position, a keeper pivotally mounted in said coin passage and having means for holding a coin in position between said plunger parts when said keeper is in an operative position, a spring tending to displace said keeper, a pivoted, releasing member engaging said keeper to hold the same in an operative position, and a member carried by said operating member, and engaging said releasing member, to hold said releasing member operative until said operating member passes beyond said first plunger part.

In testimony whereof I have signed my name to this specification in the presence of 85 two subscribing witnesses.
